CLEANING MATERIAL HOLDER

Walter J. Keller, Philadelphia, Pa.

Application January 15, 1936, Serial No. 59,290

4 Claims. (Cl. 15—209)

This invention appertains to new and useful improvements in holders and more particularly to a holder for cleaning material such as steel wool.

The principal object of the present invention is to provide a holder which can be merely set upon a pad of steel wool or similar material while in released position and then by actuating the device, grasps the material in such a way as to firmly hold it in place so that it can be used conveniently in various cleaning and abrading operations.

During the following specification other important objects and advantages of the invention will become apparent to the reader.

In the drawings:

Figure 1 represents a top plan view of the device.

Figure 2 is a vertical sectional view taken substantially on line 2—2 of Figure 1.

Figure 3 represents a cross sectional view taken substantially on line 3—3 of Figure 2 with certain of the claws removed.

Figure 4 is a cross sectional view on line 4—4 of Figure 2.

Figure 5 represents a fragmentary side elevational view of the handle portion of the holder.

Figure 6 is a fragmentary side elevational view of the retaining portion of the holder.

Figure 7 is a perspective view of the bell crank.

Referring to the drawings wherein like numerals designate like parts, it can be seen that numeral 5 represents a hollow handle of any desired shape in cross section, the upper portion of which is flared as at a. The top 6 of this handle is provided with a depressed portion 7 in the form of a trough extending inwardly from one edge thereof. A short branch trough or depression 8 extends off of the depression 7 as shown in Figure 1. The bottom of the trough 7 is provided with an elongated slot 9 through which the rod 10 is slidable, this rod 10 above the slot 9 being provided with a head 11 against which the laterally disposed end portion 12 of the strip spring 13 normally engages to hold the head in operated position, this spring 13 being suitably anchored as at 14 to one said wall of the trough 7.

The rod 10 extends downwardly in the handle 5 and connects to the laterally disposed lug 15 at one end of the bell crank 16 which is swingably mounted on the pin 17.

The lower end of the handle 5 is provided with lugs 18 which extend through openings in the base plate 19 and these lugs are bent inward-

ly as shown in Figure 2 so that the handle is positively connected to the base 19.

The base 19 is provided with radially disposed slots 20 at the edge portion thereof, opening through the edge of the base 19 and at each side of each of the slots 20 is an apertured ear 21.

Claw units generally referred to by numeral 22 in Figure 3 each consist of a U-shaped element 23 having apertured ears 24 depending from the bight portion thereof for interposition between a pair of the ears 21 on the base 19 so that a ring 25 passed through the apertured ears 21 and 24 pivotally connects the unit 22 to the base 19. The outer leg portion b of each of these units 22 is provided with spurs 26 curved in the direction of the end of the legs, while the other leg of each unit 22 is provided with a hood like structure 27 having an inclined wall 28. Each of these hood structures 27 is provided with a struck out portion bent downwardly to form a guide for a coiled compressible spring 29 which is interposed between the base plate 19 and the inner side of the hood 27 as shown in Figure 2. Thus, the tendency of the spring 29 is to force the hood upwardly and swing the unit 22 around so that the U-shaped member 23 will depend with the spurs 26 resting against a pad or mass of steel wool 30.

The retractor and detent for these units 22 consist of a plate 31 provided with a portion 32 extending through slots 33 in opposite side walls of the handle 5. This plate 31 is provided with an annular trough like formation 34, one wall of which is inclined as at 35. The edge portion of this plate 31 beyond the trough 34 is provided with a depending apron 36 vertically slotted to receive the aforementioned spurs 26.

A connector 37 having one end pivoted to the lower end of the bell crank 16 and at its other end pivoted to the ears 38 on the portion 32 of the plate 31 serves as a connector between the plate 31 and the bell crank 16.

In order to release the pad of steel wool 30, the spring 13 is pressed against the adjacent side wall of the trough 7, thus releasing the head 11 permitting the rod 10 to move to the left in Figure 2. This releases the plate 31 so that it can move upwardly and spring 29 swing the units 22 outwardly so that the pad 32 can be readily disconnected therefrom. By leaving the holder 5 in this condition, a new pad can be engaged against the base 19, or the holder upon the pad by engaging the base against the pad, and subsequently, the head 11 can be moved to the right in Figure 1 to the position shown which

will result in the engagement of the inclined wall 35 against the inclined walls 28 and this wedging or cam action will return the unit 22 to the upright position shown in Figure 2 with the spurs 26 embedded in the mass 30 and stretching the same across the bottom side of the base plate 19.

5 While the foregoing specification sets forth the invention in specific terms, it is to be understood that numerous changes in the shape, size 10 and materials may be resorted to without departing from the spirit or scope of the invention as claimed hereinafter.

Having thus described the invention, what is claimed as new is:

- 15 1. A holder of the character described comprising upper and lower plates, the lowermost plate constituting a base and the uppermost plate having a peripheral downturned slotted flange, a plurality of swingable members on the edge portion of said base and positioned adjacent the inner face of said flange, claw members on the swingable members, spring means urging the claws outwardly through the slots, cooperating means on said uppermost plate and said members for retracting the claws upon the movement of the plates toward each other, a handle connecting the plates for movement relative to each other and means carried by the handle for causing relative movement of the plates.
- 20 2. A holder of the character described comprising upper and lower plates, the lowermost plate constituting a base and the uppermost plate having a peripheral downturned slotted flange, a plurality of swingable members on the edge portion of said base and positioned adjacent the inner face of said flange, claw members on the swingable members, spring means urging the claws outwardly through the slots, a handle extending upwardly from the base, said uppermost plate being slidable on the handle and cam means between the uppermost plate and the swingable members for retracting the claws, said cam means consisting of upwardly and outwardly inclined portions on the underside of the upper plate in sliding contact with said swingable members; and means on the handle for holding said inclined portions of the uppermost plate in engagement with the swingable members.
- 25 3. A holder of the character described comprising upper and lower plates, the lowermost plate constituting a base and the uppermost plate having a peripheral downturned slotted flange, a plurality of swingable members on the edge portion of said base and positioned adjacent the inner face of said flange, claw members on the swingable members, spring means urging the claws outwardly through the slots, a handle extending upwardly from the base, said uppermost plate being slidable on the handle and cam means between the uppermost plate and the swingable members for retracting the claws, said cam means consisting of upwardly and outwardly inclined portions on the underside of the upper plate in sliding contact with said swingable members; and means on the handle for holding said inclined portions of the uppermost plate in engagement with the swingable members.
- 30 4. A holder of the character described comprising upper and lower plates, the lowermost plate constituting a base and the uppermost plate having a peripheral downturned slotted flange, a plurality of swingable members on the edge portion of said base and positioned adjacent the inner face of said flange, claw members on the swingable members, spring means urging the claws outwardly through the slots, a handle extending upwardly from the base, said uppermost plate being slidable on the handle and cam means between the uppermost plate and the swingable members for retracting the claws, said cam means consisting of upwardly and outwardly inclined portions on the underside of the upper plate in sliding contact with said swingable members, and means on the handle for holding said inclined portions of the uppermost plate in engagement with the swingable members, said means comprising a manipulating lever accessible through the upper portion of the handle and a bell crank link connecting the lever to the upper plate to raise and lower said plate.
